UNITED STATES PATENT OFFICE.

JAMES HAMILL, OF LAMBERTVILLE, NEW JERSEY, ASSIGNOR TO ASBESTOS PROTECTED METAL COMPANY, OF PITTSBURGH, PENNSYLVANIA, A CORPORATION OF PENNSYLVANIA.

APPARATUS FOR PRODUCING PROTECTED METAL SHEETS HAVING PERFORATED FIBROUS LAYERS.

1,347,852.

Specification of Letters Patent. Patented July 27, 1920.

Application filed May 9, 1917. Serial No. 167,512.

To all whom it may concern:

Be it known that I, JAMES HAMILL, a citizen of the United States, and a resident of Lambertville, in the county of Hunterdon and State of New Jersey, have invented an Improvement in Apparatus for Producing Protected Metal Sheets Having Perforated Fibrous Layers, of which the following description, in connection with the accompanying drawings, is a specification, like characters on the drawings representing like parts.

This invention relates to an apparatus for producing a novel product composed in whole or in part of fibrous material saturated or impregnated with a saturating material.

The apparatus is especially applicable for treating sheets, webs or layers of fibrous materials, such as asbestos felt or paper, wool felt, paper stock in sheet form, artificial leather, fiber board and the like, which under normal conditions resist penetration by a relatively thick or heavy saturant, whereby a superior impregnation or saturation may be obtained with a thicker or heavier saturant at a relatively low temperature, at which danger of injuring the fibrous material by high heat is avoided and a stronger and better article produced.

The invention is particularly applicable among other uses for the treatment of fibrous sheets or layers, such as asbestos paper or felt, wool felt and the like which are to be impregnated or saturated with bituminous substances, such as asphalt, or with other adhesive material, and to facilitate description, I will hereinafter refer to the fibrous material as asbestos paper and the saturant as asphalt.

The particular features of this invention will be pointed out in the claims at the end of this specification.

Figure 1 represents in section and elevation one form of apparatus embodying the invention.

Figs. 2 and 3, details of the perforating device shown in Fig. 1.

Fig. 4, a section of the paper sheet or layer applied to one surface of the metal sheet shown in Fig. 1, to illustrate the saturation of the sheet with the relatively thick asphalt.

Fig. 5, a like section with the perforations extended but partially through the sheet, 55 and

Fig. 6, a section like Fig. 4 showing the surfaces covered with asphalt.

In Fig. 1, I have represented one form of apparatus embodying the invention, which apparatus is in the main substantially such as shown in U. S. Patent No. 1,002,303, dated September 5, 1911, and is employed for producing asbestos protected metal sheets, and consists of a kettle 10 containing a bath of asphalt 12, maintained in a fluid condition by heat supplied by burners 13 or otherwise, and through which bath a metal sheet 14 is passed so as to be covered with the asphalt, which serves to cement to the opposite surfaces of said metal sheet, webs, layers or sheets 15, 16, of asbestos paper, which are taken from rolls 17, 18, of the same.

The metal sheet 14 is fed through the bath by suitable feed rolls, represented by the gears 19, 20, and is properly directed by suitable guides 21 to delivery rolls, about which the asbestos webs 15, 16, are passed, and which are represented by the gears 22, 23.

In order to obtain a superior saturation or impregnation of the paper webs or sheets 15, 16, with the asphalt 12, the said paper webs or sheets are provided with substantially small or fine perforations 25, which may extend entirely through the paper as represented on an enlarged scale in Figs. 4 and 6, or but partially therethrough as represented in Fig. 5. These perforations may be made in the paper webs by suitable devices, herein represented as prick points or projections 26 on the circumference of rollers 27, 28, which points or projections may be made in any suitable manner, and said rollers are located between the rolls 17, 18, and the delivery rollers 22, 23, and coöperate with bed rolls 30, 31, which support the paper webs 15, 16, to perforate the latter before they are brought into contact with the asphalt coated metal sheet as the latter passes between the delivery rolls.

As stated above, the perforating devices are made sufficiently thin or small so as to permit of the paper webs being perforated without injuring the paper or weakening its strength.

When the perforated paper webs are brought into contact with the asphalt coated metal sheet 14, the paper webs are adhesively attached to the metal sheet by the asphalt which covers the surfaces of the metal sheet, and the asphalt on the metal sheet is more or less absorbed by the paper webs, and a portion of the asphalt fills the perforations, which act as reservoirs or wells to feed the asphalt into the interior or body portion of the paper web or sheet, as represented by the fine lines 32 extended from said perforations, Fig. 6. The perforations remain filled with the asphalt, which when cooled form asphalt keys, rivets or bonds 33 for firmly bonding together the laminae of the paper web and also for effectively attaching the paper web to the metal sheet by a substantially large number of minute or small bonds.

As a result, the paper web is attached to the metal sheet in a superior manner and a superior protected metal article is obtained.

The webs or sheets 15, 16, may be plain or non-saturated material, or may be webs or sheets which have been previously perforated and saturated before they are used with the apparatus shown in Fig. 1.

By means of the present invention, any given felt or layer of fibrous material can be saturated with any given saturant at a much less heat than is now possible, which, besides being economical, increases the range of saturating materials with respect to those fibers which are injured by a higher heat.

So also a very much heavier saturant may be used for any given material, which results in a stiffer, stronger and better product. Furthermore the time required for saturation is shortened to a marked degree; with a corresponding increase in the commercial production.

I have herein represented one construc-

tion of device or apparatus for perforating the fibrous felt, paper or like material and for applying it to the metal sheet, but it is not desired to limit the invention to the particular construction shown.

Claims:

1. Apparatus of the character described, comprising means for coating the surface of a metal sheet with a relatively thick or heavy saturant, a bed roll to support a paper web or sheet, a perforating roll coöperating with the bed roll to perforate the paper web or sheet while the latter is supported by said bed roll, and means for applying said perforated paper web to the coated surface of said metal sheet.

2. Apparatus of the character described, comprising means for coating the opposite surfaces of a metal sheet with a liquid adhesive, means for applying sheets of material composed in whole or in part of fibrous material to the opposite surfaces of said metal sheet, and perforating devices coöperating with said fibrous sheets to provide them with substantially small perforations before they are engaged with the coated metal sheet.

3. Apparatus of the character described, comprising means for coating the opposite surfaces of a metal sheet with a liquid adhesive, means for applying sheets of material composed in whole or in part of fibrous material to the opposite surfaces of said metal sheet, perforating rolls coöperating with said fibrous sheets to provide them with substantially small perforations before they are engaged with the coated metal sheet, and bed rolls to support the said fibrous sheets while they are being perforated.

In testimony whereof I have signed my name to this specification.

JAMES HAMILL.
